United States Patent Office

Des. 186,246
Patented Sept. 29, 1959

186,246

JAR

Brooks D. Fuerst, Sylvania, Ohio, and William E. Long,
Morton Grove, Ill., assignors to Owens-Illinois Glass
Company, Toledo, Ohio, a corporation of Ohio

Application August 19, 1958, Serial No. 52,280

Term of patent 14 years

(Cl. D58—25)

Fig. 1.

Fig. 2.

Fig. 3.

Fig. 1 is a side elevational view of a jar showing our new design.

Fig. 2 is a bottom plan view of the jar shown in Fig. 1.

Fig. 3 is a fragmentary sectional view taken along the plane of line 2-2 of Fig. 1.

We claim:

The ornamental design for a jar, substantially as shown.
